UNITED STATES PATENT OFFICE

KURT BEUTHNER, OF KREFELD, GERMANY

BASE CLOSURE FOR VERTICAL GAS RETORTS AND GAS CHAMBERS

Application filed December 27, 1929, Serial No. 416,962, and in Germany January 3, 1929.

This invention relates to base-closures for vertical gas retorts and gas chambers and especially to that kind of base-closures which allow the removing of distillation products 5 from the lower part of the retort or chamber.

In the existing base-closures the door is provided with a hood, which is open at one longitudinal side, near to the inner wall of the chamber or retort.

10 The characteristic features of this invention are that the hood is divided into two halves nearly in the direction of the middle longitudinal plane of the chamber; that one half is closed and constructed as a normal 15 protecting hood for the door, while the other half is open both at the inner side towards the middle of the chamber and at one front end, and that in one front wall of the chamber a gas-outlet communicating with the inner 20 side of the open half of the hood is arranged.

The advantage of such a construction of the hood is that the gases escaping at the lower end of the chamber must continually pass through the comparatively cool middle 25 coal-core so that the gases remain cool and do not decompose. If steam is introduced through the open half of the hood it flows over the whole middle plane of the contents of the chamber, whereby a complete decomposi- 30 tion of the steam is achieved, so that a water gas of more uniform and steady composition than by means of the existing closures is obtained.

In the accompanying drawings, a base 35 closure according to the invention is illustrated by way of example.

Fig. 1 shows a vertical cross section through a gas chamber.

Fig. 2 shows a vertical longitudinal section.

Fig. 3 shows a vertical cross section through the lower part of the gas-chamber in an enlarged scale.

Fig. 4 shows a vertical longitudinal section through the lower part of the gas-chamber, also in an enlarged scale.

The gas-chamber a has at the lower end a cover o . This cover o is provided with a hood. According to the invention this hood 50 is divided into two parts in the longitudinal

direction of the chamber. Part n is closed and serves as a normal protecting and insulating hood for the closure-door o . The other part p is open at the inner longitudinal side. The lateral aperture of this open part p is 55 about in the middle longitudinal plane of the chamber a . The part p of the hood is elevated at the end at s and is also open. The open end projects into a recess i of the front wall of the chamber.

In this front wall of the chamber a a gas-outlet c communicating with the interior of the part p of the hood is arranged. The object of the elevation s is to enable a proper and unrestrained removal of the distilled 60 gases into the lower eduction pipe c .

The part p of the hood may assume any shape, but between the door o and the part p of the hood there must be a free space q for leading off the gases. Though the coal lying on the parts n and p of the hood can through the lateral aperture of the part p enter the interior of this part, it cannot fill up the entire inner space of the part p , for it lies under its natural angle of slope α (Fig. 4).

There is therefore above the coal and at its side a free passage q for the distilled gases, which can reach the pipe c through the elevated end s of the part p of the hood.

The ribs r in the open part of the hood serve as supports to relieve this part from the pressure of the coal weight and to transfer it to the base-closure o .

For the introduction of steam a duct h opens into the pipe line c . For the purpose of forming water gas such steam is blown, in the known way, through the pipe line c after the gasification of the coal, into hot coke. The steam flows through the free space q of the part p of the hood into the inside of the chamber a and it meets—and this is of special importance—the hot coke in the direction of the entire middle longitudinal plane of the chamber.

I claim:

1. A base closure for vertical gas retorts and gas chambers comprising the combination of a door with a hood; said hood is divided into two halves nearly in the direction of the middle longitudinal plane of the cham-

ber, one half is closed and constructed as a normal protecting hood for the door, the other half is open both at the inner side towards the middle of the chamber and at one front end, a gas outlet in one front wall of the chamber, said gas outlet communicating with the inside of the open half of the bonnet.

2. A base closure for vertical gas retorts and gas chambers comprising the combination of a door with a hood, said hood is divided into two halves nearly in the direction of the middle longitudinal plane of the chamber, one half is closed and is constructed as a normal protecting hood for the door, the other half is open both at the inner side towards the middle of the chamber and at one front end, and elevated at the open front end, a gas outlet in one front wall of the chamber, said gas outlet communicating with that end of the open half of the bonnet, where the hood is elevated.

3. A base closure for vertical gas retorts and gas chambers comprising the combination of a door with a hood, said hood is divided into two halves nearly in the direction of the middle longitudinal plane of the chamber, one half is closed and is constructed as a normal protecting hood for the door, the other half is open both at the inner side towards the middle of the chamber and at one front end, a recess in one front wall of the chamber, the door and the open end of the hood projecting into said recess, a gas outlet in said recess.

35. 4. A base closure for vertical gas retorts and gas chambers comprising the combination of a door with a hood; said hood is divided into two halves nearly in the direction of the middle longitudinal plane of the chamber, one half is closed and constructed as a normal protecting hood for the door, the other half is open both at the inner side towards the middle of the chamber and at one front end, a gas outlet in one front wall of the chamber, said gas outlet communicating with the inside of the open half of the bonnet, a steam pipe discharging into said gas outlet.

5. A base closure for vertical gas retorts and gas chambers comprising the combination of a door with a hood, said hood is divided into two halves nearly in the direction of the middle longitudinal plane of the chamber, one half is closed and is constructed as a normal protecting hood for the door, the other half is open both at the inner side towards the middle of the chamber and at one front end, and elevated at the open front end, a gas outlet in one front wall of the chamber, said gas outlet communicating with that end of the open half of the bonnet, where the hood is elevated a steam pipe discharging into said gas outlet.

6. A base closure for vertical gas retorts and gas chambers comprising the combination of a door with a hood, said hood is di-

vided into two halves nearly in the direction of the middle longitudinal plane of the chamber, one half is closed and is constructed as a normal protecting hood for the door, the other half is open both at the inner side towards the middle of the chamber and at one front end, a recess in one front wall of the chamber, the door and the open end of the hood projecting into said recess, a gas outlet in said recess, a steam pipe discharging into said gas outlet.

In testimony whereof I have signed my name to this specification.

KURT BEUTHNER.
